CLAIM

The ornamental design for a robot head as shown and described.

DESCRIPTION

FIG. 1 is a front, perspective view of the robot head of my design.

FIG. 2 is a front elevation view of my design.

FIG. 3 is a back elevation view of my design.

FIG. 4 is a top plan view of my design.

FIG. 5 is a bottom plan view of my design.

FIG. 6 is a left side elevation view of my design; and,

FIG. 7 is a right side elevation view of my design.

The broken lines in the drawings are for purposes of illustrating portions of the robot head and form no part of the claimed design.

1 Claim, 7 Drawing Sheets
